WARM AIR FURNACE AND RADIATOR
CONSTRUCTIONEarl W. Jorolemon, Rochester, N. Y., assignor to
General Motors Corporation, Detroit, Mich., a
corporation of Delaware

Application March 9, 1950, Serial No. 148,615

2 Claims. (Cl. 126—102)

1

The present invention relates generally to a warm air furnace and more particularly to certain improvements in the construction of the heat transfer unit of a furnace especially adapted for use of a liquid fuel burner.

The principal object of the invention is to provide a heat transfer unit designed for the efficient transfer of heat from the hot combustion gases of a liquid fuel burner to the circulating air in the heating system. The unit features a construction providing a large heat transfer area and permitting all its surfaces to be most effectively used for heating the air.

A further object is to provide a heat transfer unit of simple construction comprising a combustion shell or chamber and a radiator adjacent the upper end of this chamber which may be constructed of heavy gauge sheet metal and provided with continuous welded seams to eliminate any possibility of combustion gas leaks.

Other objects and advantages of the present invention will more fully appear from the following description of the preferred embodiment illustrated in the accompanying drawings, in which:

Figure 1 is a vertical cross-sectional view of a furnace with parts in elevation; and

Figure 2 is an exploded view in perspective of parts of the heat transfer unit.

Referring to the drawings, in Figure 1 the present invention is shown as embodied in a warm air furnace of the gravity air circulation type. It should be understood, however, that this furnace has also been designed for and can readily be employed in a forced air circulating system, wherein the present furnace construction would be mounted above or adjacent a conventional blower unit which communicates with the bottom of the furnace or with an air inlet opening in a lower portion of a side of the furnace.

The furnace is shown as provided with an external jacket or casing, indicated generally by 10, consisting of vertical sheet metal panels 11 having secured thereto a bottom wall 12 and a top wall 14. The top wall is shown as having an outlet opening 16 for the warm air to be supplied directly or through suitable ducts to the rooms to be heated. It will be understood that a suitable opening or openings would also be provided in the bottom wall 12 or in a lower portion of a vertical panel for the admission of the air to be heated as it rises or is forced upwardly through the furnace.

The heat transfer unit, which is spaced within the casing 10, comprises primarily a combustion shell, indicated generally by 18, and a radiator,

indicated generally by 20, which are constructed of relatively heavy gauge sheet metal. Although the shape of the combustion shell may vary from that shown herein, it preferably consists of a vertically extending tubular or cylindrical body 22 having a substantially flat bottom wall 24 welded to the lower end thereof and a substantially semispherical or dome-shaped top wall 26 welded to the upper end thereof. These parts of the combustion shell may be readily formed from flat metal sheets, with the body 22 bent into a cylindrical shape and welded together at overlapping edges and the top wall 26 drawn into the desired shape.

The radiator 20 comprises outer and inner hood-shaped members 28 and 30, respectively, preferably formed from flat metal sheets and drawn to the shapes shown in Figure 2. The outer member 28 is shown as having a generally flat upper wall 34 and a substantially cylindrical skirt portion 32 connected by an arcuate or toroidal portion 36. The upper wall 34 has an upwardly extending flange 38 encircling a central opening 40. The inner member 30 is preferably drawn into a generally frusto-conical shape and has a central opening 42 in its upper end which registers with opening 40 in the outer member. An upwardly extending flange 44 formed from the upper edge of member 30 circumscribes opening 42 and is positioned within the opening 40 and secured, preferably by welding, to the flange 38. Similarly, the lower edges of the outer and inner members 28 and 30 are shown as welded together, the inner member 30 preferably being provided with a downwardly extending flange 46 for this purpose. The generally annular chamber 48 thus defined functions as a duct for the passage of the hot flue gases.

A duct 52 extending from an opening 54 in the top wall 26 of shell 18 to an opening 56 in the inner member 30 of the radiator 20 provides communication between the generally annular radiator chamber and the combustion space 58 in shell 18, the ends of the duct 52 being shown as welded to the walls 26 and 30. At a location approximately diametrically opposite the duct 52 the outer member 28 of the radiator 20 is provided with an opening 58 to receive an outlet pipe or flue 60 which is welded to the outer member 28 and adapted to be connected to the usual stack or smoke pipe.

For a purpose to be hereinafter set forth, it should be noted that the over-all diameter of the annular radiator 20 is greater than the diameter of the combustion shell 18 so that the

radiator extends radially beyond the sides of the combustion shell. The semispherical upper end wall 26 of the combustion shell 18 extends upwardly into the generally conical space defined by the radiator inner member 30, thereby forming an annular hot air passage 62 between the radiator and the top wall of the combustion shell.

Near its lower end, the body 22 of the combustion shell is provided with a relatively large opening to receive a burner mounting sleeve or frame 64, which is welded to the body 22 and extends outwardly to a similar opening in the casing 10. The outer edges of the burner mounting sleeve are provided with flanges 66 to which a burner mounting plate 68 is secured, the mounting plate in turn having its outer edges fastened to the casing. A conventional fluid fuel burner of the vaporizing type with forced draft has been more or less diagrammatically shown in Figure 1. The blower 70 and controls 72 for the burner are mounted on the outer side of plate 68 and its pot 74 is positioned within the lower end of the combustion shell 18, the air tube 76 being positioned within the interjacent mounting sleeve 64.

It will be understood by those skilled in the art that other known types of fluid fuel burners than that shown herein may be used with the present furnace construction. As one example thereof, it might be mentioned that this furnace construction is adapted without modification for an oil burner of the pressure atomizing type with a conventional burner supported on the mounting plate 68 and having a firebox within the lower end of the combustion shell.

The body 22 of the combustion shell 18 is provided above the burner receiving opening with another, smaller opening to receive the inner end of a sleeve or frame 78, which is welded to the body 22 and extends outwardly through an opening in the casing 10 and secured thereto. The frame 78 mounts an observation door 80, which is preferably hinged to the frame and adapted to be swung outwardly when it is desired to observe or inspect the operation of the burner.

A wrap around wipe sheet 82, having suitable openings for the outlet flue 60, burner mounting sleeve 64 and the frame 78, is provided between the heat transfer unit and the external jacket or casing 10. This wipe sheet 82 absorbs radiant heat from the combustion shell 18 and radiator 20, this heat being picked up by the air stream rising within the passage 84 between the wipe sheet and the combustion shell. The space 86 defined by the casing and the wipe sheet functions as an insulating layer to assure more efficient air circulation and minimize heat loss.

With the above described furnace construction it will be seen that when the burner is operated the burner flame and combustion gases rise within the combustion shell 18, and the combustion gases then pass through duct 52 into the radiator chamber or passage 48 and flow horizontally in both directions around the conical member 30 to the outlet flue 60. The radiator 20 retards the flow of hot combustion gases, and all of the walls of the heat transfer unit are heated to provide a relatively large heating surface for transmitting heat to the air which rises or may be forced upwardly through the passage 84 between the combustion shell and the wipe sheet.

Since the radiator extends beyond the side of the combustion shell 18 it will be seen that the rising air will be diverted by the outer, lower edge of the radiator so that the air will flow

through the passage 62 between the conical radiator wall 30 and the top wall 26 of the combustion shell 10 and also through the passage 88 between the outer radiator member 28 and the upper portion of the wipe sheet 82. This division of the air stream further increases the heat transfer area and permits all the radiator surfaces to be most effectively used for heating the air.

It will be noted, moreover, that the present furnace is provided with a heat transfer unit of very simple construction which can be readily fabricated from flat metal sheets with continuous welded seams to eliminate any possibility of combustion gas leaks.

Various modifications in the arrangement and details of the specific embodiment described and shown herein will be apparent to those skilled in the art and are contemplated as within the scope of the present invention as defined in the claims appended hereto.

I claim:

1. In a warm air furnace provided with an outer casing, a heat transfer unit comprising a sheet metal combustion shell having a vertically extending cylindrical body with a bottom wall and a generally semi-spheroidal top wall welded thereto, a sheet metal radiator having a generally dome-shaped outer member and a frusto-conical inner member secured together to define a horizontally arranged annular passage therebetween, a wipe sheet within said casing for absorbing radiant heat from said combustion shell, said wipe sheet being laterally and inwardly spaced from said casing and surrounding said combustion shell and radiator, said outer member being provided with a substantially central opening in its upper end wall and a laterally extending duct in its side wall, said inner member having a generally central upper opening registering with the central opening in the outer member and a second opening in its conical wall portion which is approximately diametrically opposite the laterally extending duct in the outer member, the upper edges of said members defining the central openings being provided with projecting flanges welded together to form an outlet opening over the central portion of the top wall of the combustion shell, the bottom edge of said inner frusto-conical inner member being formed into a flange extending parallel to the lower side wall portion of the outer member and welded thereto so as to define a flow dividing member projecting downwardly from said annular radiator passage intermediate said wipe sheet and said combustion chamber, the top wall of the combustion shell being positioned generally beneath said radiator and partially projecting into the recess defined by said inner member, said top wall being provided with an opening which is coaxial with the second opening in the conical wall portion of the inner radiator member and a duct interconnecting said coaxial openings to provide communication between the combustion shell and the annular radiator passage, the surface of the radiator adjacent said top wall of the combustion shell forming therewith an inner passage for conveying hot air generally upwardly from the space between said combustion shell and said wipe sheet, the outer wall of the radiator being laterally and inwardly spaced from said wipe sheet and defining therewith an outer hot air conveying passage generally coaxial with said inner passage, said flow dividing member being disposed intermediate the

inlets of said passages, the smallest cross sectional area of said inner passage being substantially larger than the smallest cross sectional area of said outer passage so as to cause a preponderance of hot air to flow through said inner passage.

2. In a warm air furnace provided with an outer casing, a heat transfer unit comprising a sheet metal combustion shell having a vertically extending cylindrical body with a bottom wall and a generally semi-spheroidal top wall welded thereto, a sheet metal radiator having a generally dome-shaped outer member and a frusto-conical inner member secured together to define a horizontally arranged annular passage therebetween, said outer member being provided with a substantially central opening in its upper end wall and a laterally extending duct in its side wall, said inner member having a generally central upper opening registering with the central opening in the outer member and a second opening in its conical wall portion which is approximately diametrically opposite the laterally extending duct in the outer member, the upper edges of said members defining the central openings being provided with projecting flanges welded together to form an outlet opening over the central portion of the top wall of the combustion shell, the bottom edge of said inner frusto-conical inner member being formed into a flange extending parallel to the lower side wall portion of the outer member and welded thereto so as to define a flow dividing member projecting downwardly from said annular radiator passage intermediate said casing and said combustion chamber, the top wall of the combustion
